UNITED STATES PATENT OFFICE

2,435,938

COTTON PICKER AND SIMILAR MACHINE

Robert S. Curley, Biddeford, Maine, assignor to
Saco-Lowell Shops, Boston, Mass., a corpora-
tion of Maine

Application June 26, 1945, Serial No. 601,632

4 Claims. (Cl. 19—86)

1

This invention relates to pickers and to other machines used in the preparation of textile fibers for spinning and in which a beating mechanism is employed similar to that used in a picker.

In most types of pickers it has been customary to feed the fiber between two fluted feed rolls, or else between a feed roll and a cooperating plate; while the cotton is held under compression; and to beat it off with a rotary beater set close to the feed rolls or to the roll and the feed plate; as the case may be.

In all of these mechanisms the beater does not draw the fiber away cleanly, but leaves a fringe of fiber varying in length and hanging down from the bite of the feed rolls. The length of this fringe varies with the type of fiber; with the length of staple; and with the spacing or setting of the beater with reference to the feed rolls.

In a machine picking from evener pedals, it is necessary to set the beater comparatively "wide," or spaced further from the feed rolls than when beating from feed rolls alone; in order to avoid pulling bunches of fiber through between the pedals and the roll. And this is true whether the beater is run upstroke, as in the case of the shoddy picker; the rayon picker; and the upstroke Buckley beater; or whether it runs downstroke, as in the waste machines, openers and lappers. Because of the presence of this uneven fringe, a thorough sub-division or uniform picking of the fibers is rarely produced, and this difficulty increases with an increase in the length of fiber. The bunches pulled from the fringe hamper the cleaning of the fiber in downstroke machines and tend to produce a lumpy uneven sheet on the screens of the picker. Moreover, there is a tendency for the lap to split where these bunches are distributed throughout the sheet.

In an upstroke beater there is also a tendency for the fringe to fall back over the feed roll and to wind up or "lap" the roll. This phenomenon has proved particularly objectionable in upstroke pickers working on rayon fiber, or mixtures of rayon and cotton.

The present invention is especially concerned with the foregoing considerations, and it aims to devise a thoroughly practical solution for the problem presented by them.

The nature of the invention will be readily understood from the following description when read in connection with the accompanying drawings, and the novel features will be particularly pointed out in the appended claims.

2

In the drawings,

Fig. 1 is a vertical, sectional view through a portion of an upstroke picker re-designed to embody the present invention; and

Fig. 2 is a similar view showing the invention embodied in a downstroke picker.

Referring first to Fig. 1, the construction there shown comprises a common form of carding beater 2, revolving in a casing 3 and associated 10 in the usual manner with other picker elements including a pair of condenser cylinders, one of which is indicated at 4. It also includes a feeding mechanism of a common type comprising a feed roll 5 cooperating with evener pedals 6 across 15 which the cotton is fed by the roll into the path of the beater teeth.

The parts above described are all constructed, arranged and operated in a manner long used in the textile industry.

20 According to the present invention a supplemental roll 7 is positioned closely adjacent to the feed roll 5 closer to the beater where it will exert a control over the movement of the fiber away from the beating point. Preferably this 25 roll is set as close as possible to the path of the beater, closer than is the roll 5; and it should be driven at a speed comparable to that of the latter roll. Usually the best results are obtained by driving it at a slightly higher speed than the feed roll. In operation, it serves to support the fringe above referred to while the beater performs an additional beating operation on it. This breaks up the lumps above mentioned; results in a finer picking of the stock; and releases the 30 fiber only after it has been reduced to a considerably more uniform state than can be produced with the orthodox feeding mechanisms.

Ordinarily the feed roll 5 is driven from the intermediate gear between the evener roll and the 35 apron gear. As shown, the roll shaft is connected through gears 9, 10 and 11, to a shaft 12 carrying a sprocket wheel 13, and a chain driven by this wheel drives another sprocket wheel 14 fast on the shaft 15 to which the supplemental roll 7 is secured.

This supplemental roll may be either a plain roll, or it may be fluted, sand-blasted, or wire-wound; as in the case of an Ashworth roll. The last mentioned type of roll is shown in Fig. 1. 45 In general, the plain roll seems to work better than a fluted roll, apparently because of a better control of air currents. In most cases, however, the Ashworth roll is more effective in controlling the fringe so as to obtain a maximum 50 amount of picking by the beater while the fiber

is held in the control of this supplemental roll. For this purpose the teeth of the Ashworth type roll exert a very beneficial restraint on the fiber. They prevent it from being kicked off in bunches by the beater and retard its movement under the action of the latter sufficiently to secure the more advantageous result above described. This control is also aided by setting the supplemental roll as close as possible to the path of revolution of the beater. A further advantage of the supplemental roll at this point is that its direction of rotation is such as to reduce the possibility of either roll lapping up.

Fig. 2 shows the invention applied to a well-known commercial form of cotton picker equipped with an evener and with a downstroke beater. In this construction the cotton is fed to the beater by a feed roll 16, cooperating with the pedals 17 of an evener mechanism, which also is of a well-known type. The drive for the feed roll 16 comes through gears 18, 19, 20 and 21, and the latter gear, which is secured to the feed roll, meshes directly with a gear 22 on the shaft of the supplemental roll 23. Here again, the latter roll is set as closely as possible to the path of the beater. However, the addition of this roll permits a wider setting between the beater and the orthodox feeding mechanism. Its function is the same as that above described in connection with the upstroke beater. In Fig. 2 this supplemental roll is wound with Ashworth type wire, and the teeth are directed backwardly or opposite to the direction of rotation of the roll, as is also true in Fig. 1. This arrangement gives the roll an added hold on the stock and thus retains it more firmly while the fiber is beaten out. In most cases the best results are obtained, particularly with longer staples, in running this roll about 10% faster than the surface speed of the feed roll 16. This results in a draft of around 10% or 12% between the evener roll and the carding roll 23.

It has been found in the practical use of this invention in textile mills that it produces a far better lap than do the prior art feeding mechanisms. This is particularly true in operating on long fiber, such as rayon, or mixtures of cotton and rayon. A single beater machine equipped with this invention has been found to produce a better lap than that obtained by using two or three beaters with the old feed mechanisms.

As above indicated, this invention is useful not only in pickers, but also in other textile machines, such as those previously mentioned in which a beating operation is performed and where uniformity in the resulting lap is an important factor.

While I have herein shown and described a preferred embodiment of my invention, it is contemplated that the invention may be embodied in other forms without departing from the spirit or scope thereof.

Having thus described my invention, what I desire to claim as new is:

1. In a cotton picking machine, the combination with a rotary beater and mechanism for feeding fibrous material to said beater and presenting it thereto for the beating operation, of a supplemental roll positioned closer to the path of revolution of said beater than is said feeding

mechanism, means supporting said roll where it will engage the fringe of cotton extending from the nip of said feeding mechanism and will support it in position for the beater elements to act on its after they pass the beating point, and means for driving said roll with its surface nearest the beater running in the same direction as the adjacent surface of said beater and at a peripheral speed much slower than the peripheral speed of the beater whereby the fringe is beaten by the beater as it extends from the nip of said feeding mechanism, is fed in a partial circle by said beater and is additionally beaten by said beater as said fringe engages said roll, the surface of said supplemental roll being roughened sufficiently to restrain the movement of said fringe while the beater beats it out, whereby a more thorough sub-division of the fibrous mass and a more uniform picking operation are achieved and a smoother and more even sheet is produced.

2. In a machine according to preceding claim 1, a construction in which said supplemental roll is revolved at a slightly higher speed than said feeding mechanism operates and thereby serves to draft the fringe.

3. In a cotton picking machine, the combination with a rotary beater and mechanism for feeding fibrous material to said beater including a feed roll and an evener mechanism cooperating with it, of a supplemental roll positioned closer to the path of revolution of said beater than is said feeding mechanism where it engages and supports the fringe of fiber extending forwardly from said feed roll in the direction of movement of the adjacent surface of the beater, and mechanism for driving said supplemental roll at a peripheral speed at least as great as that of said feed roll but much slower than that of the beater, whereby said supplemental roll exerts a restraining action on said fringe, retarding its movement under the action of the beater and enabling the latter to beat out the fibrous bunches in the fringe, said supplemental roll having teeth restraining the movement of said fringe under the action of said beater.

4. In a cotton picking mechanism according to preceding claim 3, a construction in which the machine is of the downstroke type and said feed roll is positioned above the pedals of said evener and said supplemental roll is positioned immediately below said pedals.

ROBERT S. CURLEY.
